UNITED STATES PATENT OFFICE

2,423,395

OPPOSED PISTON ENGINE CYLINDER LINER

Hans Lieberherr, Winterthur, Switzerland, assignor to Sulzer Freres, Societe Anonyme, Winterthur, Switzerland

Application February 16, 1945, Serial No. 578,262
In Switzerland June 7, 1944

6 Claims. (Cl. 123—173)

1

This invention relates to an opposed-piston internal combustion engine with cooled liners inserted in its cylinders. It consists in that two liners arranged coaxially and each swept by a working piston are detachably connected to each other by means of a centre ring inserted between their ends with a sealing effect, the surfaces of contact between the liners and the centre ring having cavities which serve as collecting spaces for cooling medium and communicate with each other and with the hollow cooling spaces provided between liners and cylinder.

It is expedient to design the cavities provided in the surfaces of contact and serving as collecting spaces for cooling medium as ring passages. For the purpose of obtaining a gastight cylinder working space it is advantageous to seal the contact surfaces between the coaxial liners and the centre ring by means of a packing ring of elastic material. In order to protect the centre ring from the direct radiation of and contact with the combustion gases, it can be provided with a loosely inserted heat protective ring.

Exemplifications of the invention are shown in the attached drawings, Fig. 1 showing a longitudinal section of a first embodiment and Fig. 2 a detail of a second embodiment in longitudinal section.

In Fig. 1 the liners 1, 2 arranged co-axial in the cylinder jacket 8 of an opposed-piston engine working on the two-stroke cycle are swept by the working piston 3 and 4 respectively and are provided at the end nearest the dead space 5 with flanges 6 and 7 respectively. The liner 2 arranged on the scavenging side is equipped with inlet ports 10, and the liner 1 on the exhaust side with outlet ports 9. Between the flanges 6, 7 of the liners 1, 2 the centre ring 12 is inserted and is detachably connected to the former by means of tie-bolts 11. It is expedient for these tie-bolts 11 to be held in the flange 7 of the liner 2 on the inlet side by a screw connection. In this way, during overhauls and replacement of the liner 1 on the exhaust side, which experience shows to be subject to the intenser heat stressing and greater fouling of the two, the tie-bolts 11 can remain attached to the liner 2 on the inlet side in that, after the nuts 11a have been loosened, the centre ring 12 and the liner 1 can be drawn off the bolt 11. Thus the thread of the screw joint is saved wear and tear and can be used for a long period of service.

In order to obtain a gastight cylinder working space for the working pistons 3 and 4, a packing ring 19 of elastic material, for instance rubber,

2

is arranged between the coaxial liners by arranged flanges 6 and 7 and the centre ring 12, apart from the metallic sealing of the surfaces of contact 20. Both the centre ring 12 and the flanges 6, 7 are provided in their contact surfaces with cavities 13 serving as collecting spaces for cooling medium, which may be designed as ring passages. The cavities 13 arranged in both contact surfaces of the centre ring 12 are connected to each other through a number of passages 14. In order to obtain an increased cooling effect on the centre piece 12, the single passages 14 make an angle in axial planes and are thus conducted as near as possible to the dead space 5. From the cavities 13 of the flanges 6 and 7 a number of passages 15 lead into the hollow cooling spaces 16 provided between the liners 1 and 2 and the cylinder 8. The centre ring 12 is further equipped with the usual fitting bores 17 for fuel valves, starting valves and the like.

In the example shown in Fig. 2 the centre ring 12 is provided with a loosely inserted fire protective ring 18, which protects it from the direct radiation of and contact with the combustion gases. This protective ring 18 may be made of a heat resistant material, for instance a high alloy steel, or of an insulating material, for instance a ceramic substance. The centre ring 12 is equipped with axially directed cooling passages 14 and also with the usual fitting bores 17 for fuel valves, starting valves, etc., and can otherwise be of the same design as the centre ring shown in Fig. 1.

The present invention offers the advantage that, owing to the provision of intermediate collecting spaces 13 for cooling medium, the course of the cooling-water passages can be chosen in each of the three parts 1, 2, 12 independently of the other parts and only in the light of its own requirements, whereby a minimum concentration of stress can be obtained in the single parts 1, 12, 12. In this way the working reliability is increased, and particularly that of the centre ring 12, which is subjected to the highest pressures at high temperatures. The division of the cylinder working space into three parts further permits the liners 1, 2 to be made of a material with good running qualities, while the centre ring 12 not swept by the working pistons 3, 4 consists of a material which is chosen in the first place for its appropriate toughness and accordingly has a good notch impact strength, high resistance to scaling, corrosion and the like.

Instead of designing the collecting spaces 13 for cooling medium as uninterrupted ring pas-

sages, they could be divided up into several spaces and might communicate through passages 14, 15 with the hollow cooling spaces 16. The elastic packing ring 19 supplements the metallic sealing at the sealing surfaces 20 of the flanges 6, 7 and of the centre ring 12. In particular the packing ring 19 of elastic material prevents the entry of cooling liquid into the cylinder working space, for instance in cases when, as a result of the seizing of the working piston, the tie-bolts 11 are stretched and consequently the metal sealing at the contact surfaces 20 is temporarily impaired.

I claim:

1. A cylinder for opposed pistons comprising a liner for each piston, a center ring coaxially positioned between the two liners, means for effecting a gas-tight connection between the liners and the center ring, a cooling space at the place of contact between each liner and the center ring, passages in the center ring connecting the two cooling spaces together, a cylinder jacket for each cylinder liner, a cooling space between each liner and its jacket, and passageways connecting each cooling space between the center ring and the liners with a cooling space between each liner and its jacket.

2. A cylinder for opposed pistons as defined in claim 1 which comprises cooling spaces between the cylinder liners and the center ring that are formed as ring passages.

3. A cylinder for opposed pistons as defined in claim 1 which comprises packing rings formed of elastic material for effecting a gas-tight connection between the liners and the center ring.

4. A cylinder for opposed pistons as defined in claim 1 which comprises coaxial cylinder liners.

a center ring, the interior cylindrical diameter of the center ring being larger than the interior diameters of the liners, and a heat protecting liner for the center ring having an interior cylindrical diameter approximately the same as that of the liners.

5. A cylinder for opposed pistons as defined in claim 1 which comprises several passageways in the center ring connecting the cooling spaces between the liners and the center ring which extend in the longitudinal direction of the cylinder, said passageways being angularly disposed so as to approach most closely the inner wall of the liner at a position near the dead space of the cylinder.

6. A cylinder for opposed pistons as defined in claim 1 which comprises means for inserting tie-bolts through the center ring with one end attached to one liner and the other end in the cooling space between the other liner and the jacket whereby the nuts for the tie-bolts may be manipulated in the cooling space.
